CLAIM

The ornamental design for a firearm stock, as shown and described.

DESCRIPTION

FIG. 1 is a right side perspective of a rifle stock of a first embodiment of the present invention;

FIG. 2 is a left side perspective thereof;

FIG. 3 is a top plan thereof;

FIG. 4 is a bottom plan thereof;

FIG. 5 is front elevation thereof;

FIG. 6 is a rear elevation thereof;

FIG. 7 is a right side elevation thereof; and,

FIG. 8 is a left side elevation thereof.

The broken lines shown in the drawings indicate structure and features which form no part of the claimed design.
